UNITED STATES PATENT OFFICE.

MICHAEL E. BROWN, OF BROOKLYN, NEW YORK, ASSIGNOR TO UNION SPECIAL MACHINE COMPANY, OF CHICAGO, ILLINOIS, A CORPORATION OF ILLINOIS.

TAKE-UP DEVICE FOR SEWING-MACHINES.

No. 872,328.

Specification of Letters Patent.

Patented Dec. 3, 1907.

Application filed January 5, 1905. Serial No. 239,777.

To all whom it may concern:

Be it known that I, MICHAEL E. BROWN, a citizen of the United States, residing at Brooklyn, in the State of New York, have 5 invented certain new and useful Improvements in Take-Up Devices for Sewing-Machines, of which the following is a description, reference being had to the accompanying drawing and to the letters and figures of 10 reference marked thereon.

My invention relates to an improvement in sewing machine take-ups, of the type used on the well known Union Special Sewing Machine and illustrated for example in the 15 patents to Muther and Woodward, No. 299,569, June 3, 1884, as modified by example, by the structure illustrated in Patent No. 401,776, to Dewees, of April 23, 1889 or 615,647, Dec. 6, 1898, to Woodward. In 20 connection with the operation of sewing machines, including this type of take-up, it has been found in structures that when the machine is stopped for any reason, with, for example, the needles in the goods, that the 25 tendency of the operator is almost invariably to turn the belt wheel in the opposite direction from that in which it should be turned, and this results in winding the looper thread in the groove of the take-up, so that 30 before the machine can successfully start into operation again, this groove must be cleared of its thread.

It is the object of my invention to avoid this defect, and broadly this invention consists in the provision of a device for guiding the thread out of the groove of the take-up cam, so that it will not wind therein.

The invention may be carried out in a number of different ways, several forms of 40 which are illustrated in the accompanying drawings, in which:—

Figure 1 is a side view of a take-up mechanism for a sewing machine embodying my invention, the thread-controlling cam disk 45 being shown as having a single cam face; Fig. 2 is a view similar to Fig. 1, showing the controlling cam in a different position; the front disk being removed; Fig. 3 is a view similar to Fig. 2, showing the cam as accidentally turned backward, and my improved thread-controlling device as throwing thread off from said cam; Fig. 4 is a view in side elevation of a modified form of my device, as applied to a double cam take-up 50 mechanism; and Fig. 5 is a view in side ele-

vation of another modified form of my device.

The take-up cam 1 is of the ordinary construction, such as shown in the Woodward patent, 299,569, and is supported upon and 60 rotates with the shaft 2. Said take-up cam as shown in this patent comprises two disks arranged side by side, and spaced sufficiently to receive the end of the cast off finger 3 and retaining finger 4. Said cast off finger and 65 retaining finger are supported by a suitable bracket 5, mounted on the base of the machine. Thread guiding arms 6 are also mounted upon said bracket 5, and extend forward on opposite sides of the thread-controlling cam 1. The thread from the supply passes through guide eyes in the thread 70 arms 6.

As the thread-controlling cam rotates in the direction of the arrow shown in Fig. 1, 75 the cam shoulder 7 formed by the shape of the cam disk engages the thread running between the said eyes, and as said cam moves forward the cast off finger 3, lifts the thread up the straight face of the cam until it is cast 80 over said shoulder. The thread is then retained by the retaining finger 4. This operation of the thread-controlling cam is well known in the art, and will not need further description.

When the cam disk reaches the position shown in Fig. 2 the thread is released by the retaining finger 4, and as the slack is then practically taken up by the movement of the thread carrying members, said thread will 90 extend from one thread eye to the other in the thread finger 6. If, perchance, the machine should be turned in the wrong direction after stopping in the position shown in Fig. 2, or in fact, in any other position, the shoulder 95 8 on the thread cam 1 would engage the thread running between the thread eyes and carry the same around into the position shown in Fig. 3, and if no means were provided for casting the thread off from this 100 shoulder, it would be soon wound into the take-up and break the thread.

As a means for casting the thread from the shoulder on the cam when the same is turned in the wrong direction, I have provided a 105 cast off finger 9, which, as shown in Fig. 3, is formed integral with the cast off finger 3, and lies in the space between the disks forming the take-up cam. Said cast off finger 9 extends downward a sufficient distance, so as 110

to engage the thread, as shown in Fig. 3, and cast the same off from the thread shoulder. If the machine continued to rotate or be turned in the wrong direction, the cast off finger 9 would continue to cast the thread from the shoulder on the cam. I have also provided a cast off finger 10, which, as shown in Fig. 3, is also formed integral with the cast off finger 3. The object of this finger 10, is to throw the thread out from the cam disk, if the thread should break and be carried around the shaft by the forward movement of the cam disk.

In Fig. 4, I have shown the take-up cam, 15 as being provided with two cam faces such as shown, for example, in the patent to Woodward, 615,647; the operation of these cam faces will be obvious, from said patent. When the cam disk is moving in the direction 20 of the arrow in Fig. 4, the thread will be carried to the position indicated at 11, where the same contacts with the retaining finger 3, and is cast off from the shoulder on the take-up cam. If, however, the cam disk is rotated in the wrong direction, a thread will be 25 carried to the position shown at 12, in this figure, and the cast-off finger 9' will lift the thread to a position so that it will be cast off from the take up cam shoulder. In this figure, the thread cast-off finger 9' is made shorter than in Figs. 1, 2 and 3, but must, however, be of sufficient length to cast the thread off from the shoulder of the take-up cam. The cast-off finger 13, in Fig. 4 is 30 mounted on a bracket 14, secured to the base of the machine, and extends up underneath the shaft and around the same in the space between the cam disks and operates to throw the thread out of the space between said cam 35 disk, provided the thread is broken and is carried around the shaft by the take-up cam.

In Fig. 5 I have shown my cast off finger 15, as mounted on the bracket 14. It will be 40 obvious that the cast-off finger for throwing the thread from the take-up cam when the same is moved in the wrong direction, may be supported in any suitable manner, so long as the same is properly positioned, relative to the take up cam, as to perform its function. It will also be obvious that the cast off finger 45 may be of any shape or construction other than that shown, the essential feature being to provide a surface which will contact with the thread, and lift it or cast it from the shoulder on the take-up cam.

Having thus described my invention, what I claim as new and desire to secure by Letters Patent, is:-

1. In a take-up device for sewing machines, the combination with a grooved take-up cam and a cast-off wire, upon which the thread is guided, and additional means for guiding the thread out of the groove of the take-up to prevent winding thereon; substantially as described.

2. In a sewing machine, the combination with a grooved take-up cam, a cast-off wire, and a second wire, adapted to guide the thread out of the take-up cam groove; substantially as described.

3. A take-up device including in combination, a cam disk, thread guides arranged on each side of said cam and having eyes for the passage of the thread, said eyes being located within the outer periphery of the cam, a cast-off device acting on the thread when the cam is turned in one direction, a second cast-off acting on the thread when turned in the opposite direction; substantially as described.

4. A take-up for sewing machines having a cam surface and means upon opposite sides of its axis to cast off thread from the cam surface; substantially as described.

5. In a take-up device, a revolving cam surface, thread guides upon opposite sides of said cam surface, a plurality of means to force the thread upon the outer periphery of the cam surface, said means being positioned upon opposite sides of said thread guides; substantially as described.

6. A take-up device including in combination, a grooved cam having thread-engaging shoulders, thread guides co-operating therewith, and means located in said groove to cast the thread upon the outer periphery of said cam surface, when said cam is revolved in either direction; substantially as described.

7. A take-up device, including in combination, a disk having a cam surface and a concentric portion, thread-guiding means co-operating therewith, and a plurality of means extending beyond the outer periphery of said concentric portion for casting the thread from said cam surface onto said concentric portion; substantially as described.

8. A take-up device, including in combination, spaced cam disks, forming a groove between the same, said cam disks including a cam surface and a concentric surface, a cast-off located in the groove between said cam disks, and having a downward extension extending beyond the path of movement of the concentric portion of said cam disks; substantially as described.

9. In a take-up device, a cam surface having a groove, a cast-off in said groove for forcing the thread upon the outer periphery of the cam surface, a second cast-off located in advance in the normal rotation of said cam of the first-mentioned cast-off, and having a prong extending below the outer periphery of the take-up; substantially as described.

In testimony whereof I affix my signature, in presence of two witnesses.

M. E. BROWN.
